UNITED STATES PATENT OFFICE.

CHARLES W. EVANS, OF ROCKFORD, ILLINOIS.

FOOTWEAR.

1,046,751.

Specification of Letters Patent. Patented Dec. 10, 1912.

Application filed March 4, 1912. Serial No. 681,600.

To all whom it may concern:

Be it known that I, CHARLES W. EVANS, a citizen of the United States, residing at Rockford, in the county of Winnebago and 5 State of Illinois, have invented certain new and useful Improvements in Footwear, of which the following is a specification.

The object of this invention is to provide a pad for the ball of the foot and which is 10 located between the inner and outer soles of the shoe.

The further object of this invention is to perforate the pad so that it will be flexible, and the further object is to unite the pad to 15 a fabric which is located between the soles of the shoe and united thereto, which will prevent creeping of the pad.

In the accompanying drawings, Figure 1 is a perspective view of a shoe containing 20 my improvements in which portions are broken away to more clearly show the construction. Fig. 2 is a bottom view in which portions are broken away. Fig. 3 is a section on line *a a* Fig. 1.

25 The shoe illustrated in the drawings in the main is of the usual construction, and comprises the outer sole 1, inner sole 2, welt 9 and upper 3 suitably united by stitching.

The inner sole 2 is formed with a recess 4 30 in its underface and located adjacent to the ball of the foot of the wearer. Within the recess is located a felt pad 5 formed with openings 6 extending transverse to the length of the shoe, and in two rows. This is 35 united to a canvas lining 7 by the stitching

8. The canvas lining is connected to the meeting faces of the inner and outer soles, and the pad is cemented within the recess 4 of the inner sole and to the canvas lining. The pad is held against displacement or 40 creeping within the recess 4, by the stitching 8 and by being connected to the lining and cemented within the recess.

By locating the pad between the lining and outer sole it is protected from moisture 45 either from the foot or from outside.

In use, the pad being located to receive the ball of the foot of the wearer will form a very flexible support.

I claim as my invention.

1. A shoe comprising inner and outer soles, the inner sole formed with a recess in its underface, a pad located in the recess and formed with perforations and secured in the recess, a lining located between the 55 soles and stitched to the pad.

2. A shoe comprising inner and outer soles, the inner sole formed with a recess in its under-face, a pad located in and secured in the recess and formed with perforations, 60 and a lining located between the soles, being secured thereto and stitched to the pad.

In testimony whereof I have hereunto set my hand in presence of two subscribing witnesses.

CHARLES W. EVANS.
